UNITED STATES PATENT OFFICE.

CHARLES A. HOTCHKISS, OF BRIDGEPORT, CONNECTICUT, ASSIGNOR TO
IVES & WILLIAMS, OF SAME PLACE.

DESIGN FOR A TOY-CAP EXPLODER.

SPECIFICATION forming part of Design No. 23,356, dated June 12, 1894.

Application filed April 16, 1894. Serial No. 507,774. Term of patent 7 years.

To all whom it may concern:

Be it known that I, CHARLES A. HOTCHKISS, a citizen of the United States, residing at Bridgeport, in the county of Fairfield and State of Connecticut, have invented and produced a new and original Design for Toy-Cap Exploders; and I do declare the following to be a full, clear, and exact description of the same, reference being had to the accompanying drawing, forming a part thereof.

The figure is a perspective of a toy-cap exploder illustrating my novel design.

The leading feature of my design consists in a toy cap exploder having a shank extending upward therefrom and provided at its upper end with a ring, and an exploder through which the shank passes and which is loosely retained in position by the ring.

1 denotes the body, 5 the shank extending upward therefrom, 2 the exploder, 3 projections extending outward from the exploder and 4 the ring at the upper end of the shank to which a cord may be attached in use.

Having thus described my invention, I claim—

The design for a toy-cap exploder substantially as shown and described.

In testimony whereof I affix my signature in presence of two witnesses.

CHARLES A. HOTCHKISS.
